WALTER J. ELLIS, OF VANCOUVER, BRITISH COLUMBIA, CANADA.

PROCESS OF EMBOSsing.

1,223,484.

Specification of Letters Patent.

Patented Apr. 24, 1917.

Application filed March 13, 1916. Serial No. 83,779.

To all whom it may concern:

Be it known that I, WALTER J. ELLIS, a citizen of Canada, and a resident of Vancouver, in the Province of British Columbia, have invented certain new and useful Improvements in Processes of Embossing, of which the following is a full, true, and exact specification.

My invention relates to processes of embossing designs and the like upon paper and the like. One of the principal objects of my invention is to furnish a cheap and efficient process of preparing an embossing die for the press; to provide a die which is adaptable for use in an ordinary letter head printing press which operates much more rapidly than an embossing press.

My process consists in marking or laying out the outline of the design or die in any suitable material, preferably on a smooth and dense bristol board; cutting the die with appropriate cutting tools along the outline, thereby forming male and female dies simultaneously, placing the cut dies in their interlocked position, within a hinged or folded member of relatively flexible material, pasting or otherwise securely fastening one side of the male die to one side of the hinged member and the opposite side of the female die to the other side of the hinged member. By opening the folded or hinged member about its hinged point, it allows of a proof sheet being inserted between the male and female dies and when closed and pressed together, will produce an embossed proof. The dies or rather the hinged backing member are mounted upon type base plates ready for the press. The hinge is severed by a sharp knife as the dies are now in secure positions.

My process may be better understood by referring to the drawings in which Figure 1 is a plan view of a simple die. Fig. 2 is a central cross section of same. Fig. 3 is a similar view of Fig. 1 of compound die. Fig. 4 is a cross-sectional view of Fig. 3.

Referring more particularly to the drawings, numeral 1 indicates a backing member which is hinged as at 2. The male die 3 is shown secured to one half of the hinged member and a female die 4 is secured to the

other half. Where the backing member is folded about the hinge 2, the dies 3 and 4 interlock. It will be noted that the dies have been cut apart along their outline. Referring to Figs. 3 and 4 in which a backing member is indicated by numeral 5, a hinge by 6, the base members of male and female dies by 7 and 8 respectively. Top male and female members of the die are indicated by 9 and 10 respectively. When folded about the hinge, the dies interlock as in the previous case. In making a compound die, the top and base portions are cut as previously described and the base dies are first secured to the backing member, the top dies are next centered and secured to the base dies.

What I claim is—

1. The process of making embossing dies by drawing the design outline of male and female dies upon a relatively hard but easily cut material, cutting the said male and female dies apart along the said outlines, placing the said male and female dies between adjacent faces of a hinged and relatively flexible backing member, securing one side of the male die to the backing member on one side of the hinge, securing the opposite side of the female die to the opposite side of the said backing member respectively, securing the opposite sides of said backing member to type bases, and when said dies are in an interlocked position, severing the said hinge.

2. The process of making embossing dies by drawing the design outline of male and female dies upon a relatively hard but easily cut material, cutting the said male and female dies apart along the said outlines, placing the said male and female dies between adjacent faces of a hinged and relatively flexible backing member, said dies being in an interlocked relation to each other, securing one side of the male die to the backing member on one side of the hinge, securing the opposite side of the female die to the opposite side of the said backing member respectively, securing the opposite sides of said backing member to type bases, and when said dies are in an interlocked position, severing the said hinge.

WALTER J. ELLIS.
